TOE PROTECTING SHIELD FOR SHOES

Edward B. Sherlock, Brooklyn, N. Y.

Application August 2, 1941, Serial No. 405,156

6 Claims. (CL 36—1)

This invention relates to new and useful improvements in a toe protecting shield for open toe shoes.

More specifically, the invention proposes to characterize the toe protecting shield by a construction which may be engaged over one's stockings and over the toes, and into the shoe so as to project from the normally open toe portion of the shoe and thus protect the foot.

Still further the invention proposes that the protecting shield having a top arched section with diverging sides for engaging the sides and top walls of the vamp of the shoe when its front portions projects from the open toe of the shoe. It is also proposed that the shield be provided with a flat bottom section attached to the bottom edges of the arched top section and adapted to rest on the top face of the insole of the shoe.

Still further the invention proposes a novel arrangement for preventing water under certain conditions from entering the open toe portion of a shoe provided with a protecting shield constructed in accordance with a modified form of this invention.

Another object of the invention is the construction of a device as mentioned which is simple and durable and may be constructed and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of a lady's shoe having an open toe and provided with a toe protecting shield constructed in accordance with this invention.

Fig. 2 is a fragmentary plan view of Fig. 1.

Fig. 3 is a perspective view of the toe protecting shield, illustrated per se.

Fig. 4 is a vertical sectional view taken on the line 4—4 of Fig. 3.

Fig. 5 is a perspective view of the blank from which the top arched section of the shield is constructed.

Fig. 6 is a perspective view of one of the blanks from which the bottom flat section is constructed.

Fig. 7 is a similar view to Fig. 3 but illustrating another form of the invention.

Fig. 8 is a vertical sectional view taken on the line 8—8 of Fig. 7.

Fig. 9 is a fragmentary vertical sectional view of an open toe shoe provided with a toe protecting shield constructed in accordance with another form of this invention.

Fig. 10 is a fragmentary perspective view of one of the waterproofing strips used in Fig. 9.

Fig. 11 is a fragmentary sectional view similar to Fig. 9 but illustrating another modified form of the invention.

The toe protecting shield for open toe shoes, in accordance with this invention, includes a top arched section 10 having diverging sides 10^a and a diverging top wall 10^b. The shield is also provided with a flat bottom section 11 attached to the bottom edges of the said arched top section 10 and adapted to rest on the top face of the insole of a shoe.

The top arched section 10 is formed from a blank 10', as illustrated in Fig. 5. This blank 20 has several notches 12 along its edges to facilitate bending in of the edge portions thereof, towards the bottom flat section 11. The bottom section 11 is made from two blanks 11' (see Fig. 6) which are superimposed upon each other as illustrated in Figs. 3 and 4. The edge portions 25 of the blank 10' are engaged in between the edge portions of the blanks 11'. The contacting parts of these blanks are cemented together.

In Figs. 1 and 2 a shoe 15 has been illustrated 30 of the type having an open toe 16. The protecting shield, in accordance with this invention, is shown applied to the shoe in a position it would assume when it is engaged over a stocking and over the toe, with the foot engaged in the shoe. 35 Particular attention is called to the fact that because of the diverging side walls 10^a and top wall 10^b the toe protecting shield fits tightly into the open toe portion 16 of the vamp of the shoe 15. Preferably, the toe protecting shield should be 40 constructed of leather or other relatively stiff materials so that it maintains its position as illustrated.

In Fig. 7, the bottom section 11'' is formed with a hollow or open central area 11^a so as to 45 form narrow strip portions 11^b adjacent the diverging sides 10^a of the top arched section 10.

This arrangement will permit the toe protecting shield to spread and to fill a larger toe opening in the shoe.

In Figs. 9 and 10 a modified form of the invention is disclosed which distinguishes from the prior form in the fact that weather proofing strips 17 and 18 are mounted upon the outside 50 of the sections of the toe protecting shield and coact with the adjacent portions of the shoe to

prevent or assist in preventing, the entrance of moisture into the shoe. More specifically, the strip 17 has a relatively thick front edge portion 17^a and a thin rear edge portion 17^b. The strip 17 is cemented upon the insole and side walls of the vamp portion of the shoe 15. The strip 18 is cemented to the toe protecting shield. The parts are so arranged that when the toe protecting shield is used in conjunction with the shoe, the strip 18 nestles into the strip 17, as illustrated in Fig. 7, that is, it rests against the rear shoulder of the front edge portion 17^a, and furthermore rests upon the relatively thin rear portion 17^b of the strip 17.

The strips 17 and 18 preferably should be constructed of soft rubber, or other similar material which will not hurt the foot when the article is being used. At the same time these strips must be of such material as to aid in keeping out moisture from the shoe.

In Fig. 11 still another modified form of the invention has been disclosed which is very similar to the form shown in Figs. 8 and 9 distinguishing merely in the fact that a hook 20 is mounted upon the top portion of the top arched section 10 of the toe protecting shield and releasably engages an eyelet 21 mounted through the vamp portion of the shoe 15. The hook 20 and eyelet 21 assists in holding the toe protecting shield in position.

It is to be understood that this toe protecting shield may be made of leather, imitation leather, plastics, or of any suitable composition and manufactured in various sizes, shapes and color combinations.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A toe protecting shield for open toe shoes, comprising a top arched section having diverging sides for engaging the side and top walls of the vamp of a shoe when its front portion projects from the open toe of said shoe, and a bottom flat section attached to the bottom edges of said arched section and adapted to rest on the top face of the insole of said shoe, said bottom flat section being formed of superimposed layers.

2. A toe protecting shield for open toe shoes, comprising a top arched section having diverging sides for engaging the side and top walls of the vamp of a shoe when its front portion projects from the open toe of said shoe, and a bottom flat section attached to the bottom edges

of said arched section and adapted to rest on the top face of the insole of said shoe, said bottom flat section being formed of superimposed layers, and the bottom edges of said arched section being engaged between the edge portions of said layers.

3. A toe protecting shield for open toe shoes, comprising a top arched section having diverging sides for engaging the side and top walls of the vamp of a shoe when its front portion projects from the open toe of said shoe, a bottom flat section attached to the bottom edges of said arched section and adapted to rest on the top face of the insole of said shoe, and water-proofing strips mounted on the outside of said sections for coaction with adjacent portions of said shoe.

4. A toe protecting shield for open toe shoes, comprising a top arched section having diverging sides for engaging the side and top walls of the vamp of a shoe when its front portion projects from the open toe of said shoe, a bottom flat section attached to the bottom edges of said arched section and adapted to rest on the top face of the insole of said shoe, and water-proofing strips mounted on the outside of said sections for coaction with adjacent portions of said shoe, and comprising a strip having a thick front edge and a thin rear edge and adapted to be cemented to the shoe, and a thin strip mounted on the outside of said protecting shield and adapted to be set upon the thin portion of said first named strip directly behind its thickened front edge portion.

5. A toe protecting shield for open toe shoes, comprising a top arched section having diverging sides for engaging the side and top walls of the vamp of a shoe when its front portion projects from the open toe of said shoe, a bottom flat section attached to the bottom edges of said arched section and adapted to rest on the top face of the insole of said shoe, and fastening elements mounted on said top arched section and cooperative with the vamp portion of said shoe for assisting in holding the toe protecting shield in position.

6. A toe protecting shield for open toe shoes, comprising a top arched section having diverging sides for engaging the side and top walls of the vamp of a shoe when its front portion projects from the open toe of said shoe, and a bottom flat section attached to the bottom edges of said arched section and adapted to rest on the top face of the insole of said shoe, said bottom flat section being formed of superimposed layers, with an open central area and a narrow strip portion adjacent the side of each side portion of the toe protecting shield.
